(57) CLAIM

I claim the ornamental design for a beverage dispenser, as shown.

DESCRIPTION

FIG. 1 is a perspective view of a beverage dispenser comprising the present invention;

FIG. 2 is a front elevational view of the beverage dispenser shown in FIG. 1;

FIG. 3 is a rear elevational view of the beverage dispenser shown in FIG. 1 and FIG. 2;

FIG. 4 is a side elevational view of the beverage dispenser shown in FIG. 1, FIG. 2, and FIG. 3;

FIG. 5 is another side elevational view of the beverage dispenser shown in FIG. 1, FIG. 2, FIG. 3, and FIG. 4;

FIG. 6 is a top elevational view of the beverage dispenser shown in FIG. 1, FIG. 2, FIG. 3, FIG. 4, and FIG. 5; and,

FIG. 7 is a bottom elevational view of the beverage dispenser shown in FIG. 1, FIG. 2, FIG. 3, FIG. 4, FIG. 5, and FIG. 6.
